UNITED STATES PATENT OFFICE.

JAMES A. LOYSTER, OF CAZENOVIA, AND DANIEL M. TUTTLE, OF CANASTOTA, NEW YORK.

WORKMAN'S TIME-RECORDER.

1,280,506.

Specification of Letters Patent.

Patented Oct. 1, 1918.

Application filed December 19, 1916. Serial No. 137,883.

To all whom it may concern:

Be it known that we, JAMES A. LOYSTER and DANIEL M. TUTTLE, citizens of the United States of America, and residents of 5 Cazenovia and Canastota, respectively, in the county of Madison, in the State of New York, have invented new and useful Improvements in Workmen's Time-Recorders, of which the following, taken in connection 10 with the accompanying drawings, is a full, clear, and exact description.

This invention relates to certain improvements in workmen's time recorders, involving the use of a time-card somewhat similar 15 to that set forth in our pending application, Serial No. 84,333, filed March 15, 1916, in which the card bears a series of, in this instance seven, definite concentric spaces, one for each day of the week, the concentric 20 spaces being divided into twelve equal radial spaces representing twelve working hours of a day and each hour space subdivided into ten equal spaces representing one tenth of an hour or six minutes, the hour 25 spaces being numbered clockwise from 1 to 12 inclusive.

The main object is to provide simple means for recording in or upon the proper space of the card the time of arrival and 30 departure of the corresponding workman or the beginning and ending of work upon any job for which the card is designated by simply inserting the card in the machine and operating a suitable manual.

Another object is to provide means whereby the record of "ins" and "outs" may be 35 contained on the same card through the twenty-four hours of any day, and at the same time distinguishing the "day" records 40 from the "night" or "overtime" records, so that the timekeeper may readily compute the total wage due for either period.

A further object is to prevent any possibility of making a record upon the card 45 in case it should be improperly inserted into the machine.

Other objects and uses relating to specific parts of the recorder will be brought out in the following description.

50 In the drawings—

Figure 1 is a front elevation of a workman's time recorder, embodying the various features of my invention.

Fig. 2 is an enlarged horizontal sectional

view of the same machine taken on line 55 2—2, Fig. 1.

Fig. 3 is a vertical sectional view of a portion of the prime mover taken in the plane of line 3—3, Fig. 2.

Figs. 4 and 5 are enlarged transverse vertical sectional views taken, respectively, on lines 4—4 and 5—5, Fig. 1.

Fig. 6 is a detail sectional view taken in the plane of line 6—6, Fig. 2.

Fig. 7 is a longitudinal vertical section 65 taken in approximately the plane of line 7—7, Fig. 2.

Fig. 8 is a face view of one of the workman's time-cards as used in the recorder.

The recorder shown comprises a case —1— 70 having suitable guides —2— and —2'— opening through its upper side for permitting the insertion of an impression-receiving element, such as a time-card —A—, into one or the other of a pair of impression-making devices presently described, for recording, respectively, the times of arrival and departure or "ins" and "outs" of a workman or the times of beginning and ending of work on any particular "job" for 80 which the card may be designated, said guides being readily distinguished by the words "in" and "out" printed or otherwise impressed thereon in plain view of the operator.

The impression-making devices are preferably of the "punch-and-die" type housed within the case —1—, and each comprises a pair of coaxial circular disks —3— and —3'— arranged end to end in slightly spaced 90 relation so that the intervening space will be in exact vertical alinement with the corresponding guides —2— and —2'— and of just sufficient width to permit the card —A— to pass easily between the adjacent 95 faces of said disks.

The disks of each pair are rotatably mounted on separate coaxial bearings —4— and —4'— and are provided with spirally arranged rows of registering apertures —5— 100 and —5'— extending therethrough parallel with their axes for receiving suitable punches or plungers —6— which are additionally supported by a supplemental guide disk —7— and are movable across the space 105 between the disks —3— and —3'— against the action of separate retracting springs —8— for punching holes in the interposed

card —A— in a manner hereinafter described.

The guide disks —7— are suitably secured to axially extending posts —9— on the adjacent sides of the corresponding disks —3— and —3'—, as shown in Fig. 5, and, therefore, rotate with the last-named disks to better support the plungers —6— against binding, and at the same time to limit the opening movement of said plungers by the springs —8— which are interposed between suitable shoulders on the plungers and the adjacent faces of the disks —3— and —3'—, leaving the cutting ends of the plungers normally at one side of the card space between the last-named disks.

The plungers or punches —6— of each impression-making device extend around the axis of the disks —3— and —3'— in an involute curve of one convolution or through a complete circle and in equally spaced radial lines so that their distances from the center of the disks gradually diminish from one end to the opposite end of the series, the number being twice that of the concentric spaces on the time-card —A—, or fourteen in each series, two for each of the seven days of the week, coupled in sequence from end to end of the series.

The distances of the several couples of plungers from the center of the disks correspond sequentially to the distances of the several concentric spaces from the center of the card —A— when the latter is placed coaxially with said disks ready to receive an impression, but the distance of the punches of each couple from the center differs in such manner that the one farthest from the center will punch the card near the outer edge of its concentric space to represent one end of a period of "day work," while the one nearer the center will punch the card in the same space, but nearer the inner margin thereof, to represent one end of a period of "night work" or "overtime."

The form of the punches for making the "in" records are different (in this instance round) from that of the punches for making the "out" records, which, in this instance, are square, thus producing distinctive holes in the corresponding concentric spaces of the card —A—.

The cutting or punching efficiency of the punches is greatly increased by providing the latter with reduced hardened metal cutting ends playing in corresponding apertures in hard metal linings —10— on the adjacent faces of the disks —3— and —3'—, while the remaining portions of the apertures, particularly in the female die-disk —3'— are relatively larger than those in the linings —10— to allow the punched-out portions of the card to readily fall away.

Suitable means is provided for properly centering the card —A— in either of the

guides relatively to the corresponding sets of disks —3— and —3'— and also for preventing the operation of the punches in case the card should not be properly centered to receive correct impressions, and, for this purpose, each workman's card or "job" card, as the case may be, is provided with a hole —a— in the center of its concentric series of day spaces of sufficient size to receive a centering plunger —11—.

This plunger is reciprocally movable in coaxial guide openings in the bearings —4— and —4'— and disks —3— and —3'—, as shown more clearly in Figs. 2 and 4, but is normally withdrawn to the side of the card space between the disks at which the bearing —4— is located so as to allow the card to be inserted in said space and its central hole —a— registered with the adjacent end of the plunger, under which conditions the plunger may be moved endwise into the opening —a— of the card to properly center the latter while the punch impressions are being recorded.

As a further means for assuring the proper centering of the cards, one corner of the end thereof which is to enter the guide first is recessed or notched at —a'— to receive a corresponding ledge or projection —12— at the inner end of each of the guides —2— and —2'— so that if the card is properly inserted in either guide, its notch —a'— will register with the adjacent ledge —12— and cause its hole —a— to register with the plunger —11— ready for the recording operation.

But, on the other hand, if the card is inserted in either guide so that any of its other corners encounter the ledge —12—, its central hole —a— will be out of alignment with the plunger —11— and the interposed portion of the card will prevent the operation of the plunger and recording punches, as will be apparent from the following description.

That is, the plunger —11— and punches —6— are operated manually by the workman to record the times of beginning and ending of his work through the medium of an external hand-crank —13— or equivalent device on one end of a suitable shaft —14— which is journaled in the case —1—.

Secured to this shaft —14— is a pair of forked arms —15— coöperating with the grooved hubs, as —16—, of a pair of disks —17— which are movable rotarily and axially upon their respective bearings —4— for operating any one of the corresponding set of punches —6—.

These forked arms —15— are connected by springs —18— to separate upright levers —19— of the first kind having their upper ends connected to the outer ends of the corresponding plungers —11— to shift the latter axially and their lower ends connected by links —20— to suitable rock-arms —21—,

which, together with the levers —19—, are pivoted to the case —1—, as shown in Figs. 4, 5 and 6.

The annular grooves in the hubs —16— 5 are somewhat wider than the portions of the arms —15— engaged therein so as to allow a limited movement of said arms before operating the disks —17— or punches controlled thereby, during which limited movement the springs —18— will operate the levers —19— for forcing the plungers —11— endwise and causing one of them to enter the registering central opening in the card which has previously been inserted in 15 the corresponding guide to receive the impression of the punch then registering with the operating part of the disk —17—.

Each disk —17— is provided with a radial rib —17'— adapted to register successively 20 and separately with the punches —6— of the corresponding set, and when the card is properly placed in one of the guides and immediately following the entrance of the plunger —11— into the central opening of 25 such card, the continued rotary movement of the hand-crank —13— in the same direction causes the rib —17'— to engage and operate the punch —6— which may be registered therewith to punch a hole in the card 30 in the space corresponding to the day and time when this operation takes place.

If, however, the card should be placed in one of the guides with its hole *a* out of registration with the corresponding plunger, 35 it would act as a stop to prevent the inward movement of such plunger, while the companion arm —15—, as actuated by the hand-crank —13—, would simply move through its limited arc as determined by the 40 width of the groove in the hub —16— against the action of the spring —18—.

Under these conditions, provision is made 45 to prevent further movement of the arm —15— and disk —17— consisting in arranging the inner ends of the links —20— normally in the paths of shoulders —15'— on the hubs of the arms —15—, so that if either plunger is stopped by the presence of a portion of the card, the shoulder —15'— 50 will encounter the adjacent end of the link —20— and thereby prevent the operation of the punch with which the rib —17'— of the punch-actuating disk —17— may then be registered.

The card —A— is provided with a time-indicating dial —B— consisting of a series 55 of, in this instance seven, concentric spaces, one for each day of the week, which are divided by radial lines into a series of, in 60 this instance twelve, equal sectors, one for each hour of a twelve hour day, and numbered clockwise from 1 to 12, each sector being subdivided by radial lines into ten equal spaces or six-minute intervals of time.

Suitable chronometer-controlled or chro-

nometer-actuated means is provided for rotating the punch-actuating disk —17— intermittently one six-minute space of the card-dial —B— at a time, or one complete revolution every twelve hours, said means consisting, in this instance, of a thirty-tooth ratchet wheel —22— and a pawl —23— which is mounted on a lever —24— and operated to rotate said wheel one tooth space at a time by a spring motor —25—.

A solenoid —26— is connected to the lever —24— to retract the pawl against the action of the spring —25—, said solenoid being electrically connected with a suitable chronometer-actuated circuit closer —27—, Fig. 1, capable of energizing the solenoid intermittently once every six minutes.

This ratchet wheel —22— is secured to a shaft —28— carrying a pinion —29— which meshes with another pinion —30— on a 85 separate shaft —31—, said shafts —28— and —31— being journaled in the case —1— parallel with and in a vertical plane between the disks —17— (see Figs. 2 and 7).

The ratchet wheel —22— is adapted to be 90 locked in each position of adjustment by the pawl —23—, and for this purpose is provided with a concentric series of shoulders —22'— adapted to be engaged by shoulder —24'— on the lever —24— as the pawl is advanced by the spring —25—, said ratchet wheel being also held against backward movement by a detent —23'—.

The solenoid —26— is provided with an adjustable stop —26'— for limiting the 100 movement of its plunger in one direction to a degree just sufficient to withdraw the pawl —23— from one tooth and engage it with the next adjacent tooth.

Both of the disks —17— are provided 105 with peripheral gear teeth meshing with opposite faces of the pinion —30—, the gears and pinion being of such ratio that each intermittent movement of the ratchet wheel —22— will cause the disks —17— to move 110 through an arc corresponding to one of the six-minute subdivisions on the dial —B— or one complete revolution every twelve hours.

The disks —3— and also the disks —3'— 115 are provided with peripheral gears, all meshing with an intermediate pinion —32— which is loose on the shaft —31— for a purpose presently described, the ratio being the same as that between the pinion —30— and gear-disks —17—.

The pinion —32— and incidentally the disks —3— and —3'— are driven by the pinion —30— through the medium of an escapement mechanism adapted to be automatically tripped once during each revolution of the disks —17— for a purpose presently described, and consists of a pawl or plate —33— slidably mounted in a diametrically extending recess in the end face 130

of the pinion —30— adjacent the pinion —32— and provided with a pair of reversely arranged yielding stop pawls —34— at opposite sides of the shaft —31— around 5 which the plate or pawl —33— extends.

These stop pawls —34— are spring-pressed in the direction of rotation of the pinions —30— and —32— to alternately engage one or the other of a series of, in this 10 instance four, stop pins —35— on the adjacent end of the pinion —32— in equally spaced relation so that when the plate or pawl —33— is moved diametrically in one direction one of the pawls will be in position to engage one of the pins, while the other pawl will be withdrawn from engagement with another pin, previously engaged thereby.

The length of the pawl or plate —33— is 20 about equal to the diameter of the gear —30— upon which it is mounted, and its ends are tapered or pointed so that when moved in either direction to its limit, its end in the same direction will lie in the path of 25 movement of a shoulder —36— on one of the disks —17— to be engaged thereby and shifted in the opposite direction to cause the other pointed end to be engaged by the same shoulder at the end of the next revolution of the same disk.

The loose pinion —32— is connected by a coil spring —37— to a coaxial gear —32'— which is also loose on the same shaft —31— and meshes with one of a pair of tight gears 35 —38— on a stub shaft —38'—, the other gear —38— meshing with a tight gear —39— on the shaft —31— adjacent the gear —32'—.

The gears —32'—, —38— and —39— are 40 so proportioned as to cause the loose gear —32'— to travel at a slightly less rate of speed than that of the pinion —32—, while the disks —3— and —3'— are being driven at the same speed as the disks —17— by 45 their respective pinions —32— and —30— so that the slight difference in the speed of rotation of the spring-connected gears —32— and —32'— causes the coil spring —37— to be wound up or placed under 50 greater tension during each complete revolution of the disks —3— and —3'— and —17— sufficient to drive the pinion —32— one pin (35) space backward, in this instance, one-fourth of a revolution as soon 55 as said pinion —32— is released by the tripping of the pawl —33— through the medium of the shoulder —36—.

This limited backward movement of the pinion —32— is instantaneous and causes 60 the disks —3— and —3'— to move backward one punch space so as to bring the next adjacent punches into registration with the ribs —17'— of the actuating disks —17—, it being understood that the pinion —30— 65 and gears of the disks —17— are timed to

cause the shoulder —36— to alternately engage and trip the pawl —33— in one direction at the end of one revolution of the shoulder-carrying disk —17— and in the opposite direction at the end of the next revolution of the same disk, and that the punches —6— are arranged to successively register with the ribs —17'— after each tripping operation of the pawl —33— as the disks —3— and —3'— are shifted at the end of each 70 twelve hours of the seven days.

For example, if the disks —3— and —3'— and —17— are in the position shown in Fig. 7 with the ribs —17'— registering with the outermost punch —6— and the pawl —33— 80 about to be engaged and tripped by the shoulder —36—, the day, as Monday, and the time of day, as just before six o'clock p.m., then by properly inserting the time-card —A— in one of the guides, as —2— and operating the hand-crank —13—, both disks —17— and —17— will be moved endwise to operate the outermost punches and will punch a hole in the card near the outer margin of the outermost or Monday space and 90 just preceding the radial division corresponding to six o'clock p.m., and indicates the end of an ordinary twelve-hour day's work.

Now, as the disks —3— and —3'— and —17— continue to be rotated by their respective pinions —30— and —32—, the shoulder —36— will engage and trip the pawl —33— at six o'clock p.m. and allow the spring —37— to retract the pinion —32— 100 one quarter turn, as determined by the stop pawls —34— and pins —35—, thereby turning the disks —3— and —3'— backward one punch space and registering the next punches of each series with their corresponding ribs —17'— so that if the card is again inserted in either guide and the disk —17— operated before the next shift is made or during the succeeding twelve hours, another punch hole will be made in the card in the same 105 annular space, but near the inner margin thereof and in the radial space corresponding to the time of day at which the punching operation takes place, and indicating that the workman has worked nights or 110 overtime.

In like manner, each couplet of punches may be operated to record the "ins" and "outs" during the entire twenty-four hours of each day and each of the seven days of 120 the week without special attention from the operator, other than to properly insert his card in the required guide and to then turn the hand-crank —13—, the other operations being entirely automatic.

Secured to the front of the case —1— is a suitable clock dial —40—, around which are movable ordinary minute and hour hands —41—, the latter being actuated intermittently from the main shaft —28— 130

through the medium of a clock train —42— to give the time of day.

What we claim is:

1. In a workman's time recorder of the character described, a card-holder in combination with a plurality of impression-making devices, chronometer-controlled means for simultaneously moving said devices about an axis relatively to said holder, 5 manually-operated means for operating one of said devices during one cycle of movement to make impressions on the card, and means for shifting the first-named means at the end of each cycle to register another one 10 of said devices with the second-named means during another cycle of movement.
2. In a workman's time recorder of the character described, the combination with a time-card having concentric spaces for receiving impressions of a workman's "ins" or "outs" and a holder therefor, of a rotary support having a spirally arranged series of impression-making devices thereon, chronometer-controlled means for rotating said support about an axis coincident with the center of said spaces, and manually-operated means for operating one of said devices during one cycle of movement of said support to make an impression thereon.
3. In a workman's time recorder of the character described, a card-holder in combination with a rotary support having impression-making devices thereon at different distances from its axis, chronometer-controlled means for rotating said support step by step about said axis, manually-operated means for actuating one of said devices to make impressions on the card during one cycle of movement of the support, and means 40 for shifting said support at the end of said cycle to register another one of said devices with the last-named means during the next succeeding cycle.
4. In a workman's time recorder of the character described, a card-holder in combination with impression-making devices arranged spirally about an axis at right angles to the card in said holder, chronometer-controlled means for moving said devices step by step about said axis, a rotary member registering with one of said devices and moving in unison therewith about said axis during one complete revolution, manually-operated means for moving the registering member axially into engagement with said device for making an impression on a card in the holder, and means for shifting the first-named means at the end of each revolution to register another one of said devices with the last named means.
5. In a workman's time recorder of the character described, the combination with a time-card having concentric spaces divided into sectors representing equal intervals of time, impression-making devices, one for each space, chronometer-controlled means for successively registering said devices with their sectors, and means for imparting another movement to each device to make an impression in the sectors with which it is registered.
6. In a workman's time recorder of the character described, a card-holder in combination with impression-making devices arranged about an axis at different distances therefrom, chronometer-controlled means for moving said devices about said axis, means for operating said devices one at a time to make an impression on the card, and automatic means for shifting the first-named means relatively to the second-named means for registering different devices with said second-named means once during each revolution of the first-named means.
7. In a workman's time recorder of the character described, the combination with a time-card having concentric spaces representing days of a week, said spaces being divided circumferentially into equal sectors representing intervals of a day, of a holder for said card, a support movable about an axis coincident with the center of the concentric spaces of the card, a series of impression-making devices mounted on said support in registration with the concentric spaces, chronometer-controlled means for rotating said support step by step to successively register said devices with the sectors, of their corresponding concentric spaces, and means for operating said devices one at a time for making impressions in the sectors with which they may be registered.
8. In a workman's time recorder of the character described, the combination of a guide for receiving a workman's time-card, a rotary support, a series of impression-making devices mounted on the support about the axis thereof and at gradually diminishing distances from said axis from one end to the other end of the series, an actuating member for said devices, automatic means for shifting said support rotarily step by step once during each complete revolution to successively register said devices with the actuating member, and means for moving said member axially to operate the device which is registered therewith.
9. In a time recorder of the character described, a rotary carrier having a series of axially movable stamping devices arranged about its axis in equally spaced radial lines and at gradually varying distances from said axis from one end to the other end of the series, a rotary member having an independent axial movement for operating said devices one by one to make an impression, means for moving said devices step by step about said axis to successively register the devices with said member, means for moving the member axially for operating the device

130

- which is registered with said member, and means for holding an impression-receiving member in the path of the operated stamping device.
- 5 10. In a time recorder of the character described, a rotary carrier having a series of axially movable stamping devices arranged about its axis in equally spaced radial lines and at gradually varying distances from 10 said axis from one end to the other end of the series, chronometer-controlled means for rotating said carrier and releasing it at the end of each revolution, a rotary member synchronized with the movement of the carrier to rotate therewith during such revolution and having an independent axial movement for forcing the devices to their stamping position, means for shifting the carrier rotarily when released for successively registering the stamping devices with their actuating member, and means for moving said member axially for operating the stamping device which is registered therewith.
- 15 11. In a time recorder of the character described, the combination of a rotary carrier having a series of impression-making devices arranged spirally around the axis thereof in spaced relation and at equal angles from the center, means for supporting a 20 time card in position to receive impressions from said devices, manually-operated means registering with one of the devices for operating the same to make impressions upon the card, chronometer-actuated means for 25 rotating said support, and additional means for changing the relation between the rotary support and said manually-operated means so as to cause the latter to register with a
- different impression-making device at the end of each cycle of movement of the rotary support.
12. In a time recorder of the character described, the combination with a card having an annular space for receiving impressions, impression-making devices movable about 45 the center of said space at different distances from said center, means registering with one of said devices during one revolution for operating the registering device to make impressions in one concentric line in said space, 50 and means for changing the relative positions of said devices, and operating means at the end of such revolution so as to bring the other device into registration with said operating means.
13. In a time recorder of the character described, the combination of separate holders for an impression-receiving member, rotary supports, one for each holder, chronometer-actuated means for rotating said supports 60 simultaneously, each of said supports having a series of impression-making devices arranged spirally around the axis thereof, those of one support being different from those of the other support and manually-controlled means for operating said devices to make their impressions upon the receiving member which may be registered therewith.
14. In witness whereof we have hereunto set 70 our hands this 13th day of December, 1916.
